UNITED STATES PATENT OFFICE.

JEANTY DÉNÉCHAUD, SR., OF SAN FRANCISCO, CALIFORNIA.

LAYING AND SECURING RAILS IN ROAD-BEDS OF RAILWAYS.

SPECIFICATION forming part of Letters Patent No. 299,208, dated May 27, 1884.

Application filed December 17, 1883. (No model.)

To all whom it may concern:

Be it known that I, JEANTY DÉNÉCHAUD, Sr., of the city and county of San Francisco, and State of California, have invented an Improvement in Laying and Securing Rails in Road-Beds of Railways; and I hereby declare the following to be a full, clear, and exact description thereof.

My invention relates to a new and useful improvement in laying and securing rails in the road-beds of railways; and it consists in embedding in the cross-ties the base and lateral flange of a peculiar rail, and in securing it by a novel brace or clamp, the base of which is also let into the cross-tie, as I shall herein-after fully explain.

The object of my invention is to prevent spreading of the rails by securing them to the cross-ties so firmly as to give great solidity. My invention is applicable to any railway now in existence, but is more especially adapted to be used in connection with my safety railway-car heretofore patented by me, and in which rollers secured by arms to the car are adapted to be projected into the groove of the rails to prevent derailment.

In any road a great object to be gained is to prevent the rails from spreading. If this can be done, many accidents will be averted; but when the rails are to be used with my safety-car it is of prime importance that they shall be strong enough and laid firmly enough to resist the strain of the projected rollers, and to remain accurately in place without spreading, so that the rollers may always find their bearing when projected.

Referring to the accompanying drawings, Figure 1 is a plan of my rail, showing the clamps for securing them in position. Fig. 2 is a vertical cross-section of same, showing the manner of laying them. Fig. 3 is a plan of a slightly-modified rail and means for clamping. Fig. 4 is a cross-section of same. Fig. 5 is a cross-section of a rail resembling the common form now in use, but with my flange formed with it, and showing how it is laid.

A is the rail. This is formed in a T shape, with an outer and inner groove, the rolling surface being preferably flat. It has formed with it on its outer side an upwardly-extending flange, *a*, and a downwardly-extending

flange, *a'*. In laying the rail its base is imbedded in the cross-tie *B*, and its lower flange, *a'*, extends well down into the tie.

C is the brace or clamp. This is of an L shape, and consists of a body of about an equal height with the back of the rail, and an outwardly-extending flange, *c*. On its face is formed a curvilinear bulging lug, *d*, preferably hollow for the sake of lightness. This clamp is also embedded in the cross-tie, and fits its curved lug *d* into the outer groove of the rail. Bolts *e* pass through the clamp and rail, one at the top through the upper flange of the rail, and one at the center through the lug. The head of this latter bolt is to be countersunk, as shown, to preserve a smooth surface on the inner groove, to adapt it for use in connection with my safety railway-car. A spike, *b*, is driven through the flange *c* of the clamp into the cross-tie. At the joint of two rails the clamp *C* is made sufficiently long to brace both rails.

By embedding both rails and clamps in the ties, great stability is given them, and by clamping them together thus securely they are not liable to spread, but will remain firm and even. The embedded flange of the rail of itself gives great firmness. This rail, it will be seen, can be reversed.

A modification of this rail, made for the sake of economy and to preserve the style now in use as nearly as possible, is shown in Figs. 3 and 4. Here the upper flange, *a*, is omitted, the rail being provided with a lower flange only, which, together with the base of the rail, is embedded, as in the first rail, in the cross-ties. The top of the rail is of the common shape, and the clamp is made to conform to the modified rail by reducing the height of its body. It is secured to the rail by a single central bolt; but in case it should be found impracticable to change entirely the present system of rails and means for securing them, I show in Fig. 5 but a slight change from the present rail. This has the addition of the flange *a'* embedded in the tie, as is also the base of the rail. The ordinary spikes secure it to the cross-ties, and the fish-plates are here shown as lying on the inside, to keep the outer groove smooth in case it should be desired to use the rail in connection with any safety-car.

having rollers adapted to fit the outer groove.

The clamps or braces shown may be made of wood as well as iron, thus making them more economical and equally as strong.

5 This improvement in laying and securing the rails will give a great economy in cross-ties, because they may be put at wider distances and still give solidity to the rails, as the latter are embedded in them.

10 I am aware that prior to my application railroad-rails constructed with flanges adapted to fit grooves formed in the cross-ties had been made, and such I do not claim; but

What I do claim, and desire to secure by 15 Letters Patent, is—

1. In the road-bed of a railway having cross-ties B, the rail A, having a flange, a', the base of said rail and its flange being embedded in the cross-tie, in combination with the L-shaped 20 brace or clamp C, having a curvilinear or bulg-

ing face, d, fitting the outer groove of the rail, said clamp being bolted to the rail, and having its base embedded in the cross-tie and spiked thereto, substantially as herein described.

2. In the road-bed of a railway having 25 cross-ties B, the rail A, having the lateral flanges a a', and side grooves, in combination with the L-shaped clamp or brace having a curvilinear or bulging lug d on its face, fitting the outer groove of the rail; and a means for 30 securing the clamp to the rail and the rail and clamp to the cross-tie, substantially as herein described.

In witness whereof I have hereunto set my hand.

JEANTY DÉNÉCHAUD, SR.
